UNITED STATES PATENT OFFICE.

FREDERICK BECKORD, OF WHITE HOUSE, NEW JERSEY.

PAINT MIXER.

Application filed May 12, 1926. Serial No. 108,558.

The invention relates to paint mixers adapted to be manually operated and of a plunger type and comprising a dished member inverted, and provided with an interrupted marginal flange extending upwardly and which dished member when forced downwardly will cup the paint and cause downward currents of paint during the downward movement of the device, and upon upward movement of the device will suck or cause an upward movement of paint pigments adjacent the bottom of the can, thereby insuring a quick and rapid mixing of the paint. The upwardly extending flanges carried by the dished member cause the device to partially cup the liquid in its upward movement thereby setting up upward and outward currents in the can, consequently in connection with the dished member forms a mixing device which has a mixing action on its downward and upward movement.

A further object is to provide the under side of the dished member with a transverse notched rib or flange which extends below the plane of the lower side of the dished member and which flange, during the mixing operation, may be forced into the partially solidified paint pigments in the bottom of the can for breaking up and dislodging the same so upon an upward movement of the device, said paint will be sucked upwardly therewith.

A further object is to make the dished member rectangularly shaped, and to provide the dished member with a plurality of downward and outwardly inclined triangularly shaped surfaces, which surfaces will deflect liquid downwardly and outwardly in opposite directions thereby insuring a more perfect mixture.

A further object is to form the dished member from a single piece of sheet metal bent upon itself to form the cutting flange, and bent outwardly from the upper edges of the flanges of the cutting flange and interengaging means at opposite sides of the flanges for holding the triangularly shaped inclined planes together.

A further object is to provide a handle member, the lower end of which handle

member terminates in spaced downwardly extending arms, which arms extend downwardly through the dished member at opposite sides of the dislodging flange and terminates in hooked portions extending through the dislodging flange in opposite directions, thereby bracing the flange and preventing transverse spreading of the parts forming the flange.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a perspective view of the mixing device.

Figure 2 is an enlarged front elevation of the lower portion of the mixing device.

Figure 3 is a top plan view of the dished agitator.

Figure 4 is a bottom perspective view of the dished agitator.

Fig. 5 is a detail perspective view of the central portion of the dished agitator, showing the same partially spread to better show the structure.

Referring to the drawing, the numeral 1 designates the dished agitator, which member has its chamber 2 downwardly disposed and is preferably formed from triangularly shaped members 3, which incline downwardly and outwardly and have corners terminating adjacent the center of the mixing device. The triangularly shaped members 3 are preferably formed integral with the flanges 4, which when bent together form a diagonally extending paint dislodging and cutting flange 5. The adjacent edges of the triangularly shaped portions 3 are provided with interengaged flanges 6 which prevent spreading of the triangularly shaped members 3 in relation to each other and at a right angle to the cutting and dislodging flange 5. The lower ends of the triangularly shaped members 3 terminate in upwardly

extending flanges 7, the ends of which are in spaced relation thereby forming discharge passages 8 at the corners of the device, through which liquid may pour or pass as the device is moved upwardly in a body of paint. Flanges 7 cut the paint on the upward movement and set up upward currents, therefore it will be seen there is a stirring action on the upward movement of the device 10 as well as on the downward movement thereof. Upon the downward movement of the device in a can of paint, the downwardly and outwardly inclined members 3, which form the chamber 2, not only cut the material and set up currents but deflect currents downwardly and outwardly, consequently cause currents to engage the bottom of the receptacle for bringing up the dislodged paint pigments from the bottom of 20 the receptacle.

Flange 5 extends below the lower end of the mixing member 1, and on the end of the downward stroke, cuts or imbeds itself in the solidified paint in the bottom of the can, thereby partially dislodging the same, at which time the operator may impart a slight rotation to the twisted handle member 9 which will further dislodge the paint, and allow the same to be sucked upwardly upon 30 the upward movement of the device. Flange 5 is preferably provided with a plurality of notches 6, which allow the flange to be easily imbedded and at the same time allows a mixing action upon a partial rotation of the device. Twisted handle member 9 is preferably formed from a single piece of relatively heavy wire twisted together as shown in Figures 1 and 2, after it is passed through a horizontally disposed handle member 10. The lower ends of the wires 11 which form the handle member 9 terminate in oppositely extending arms 12, which arms terminate in vertically disposed arms 13 which extend downwardly through apertures 45 14 in oppositely disposed triangularly shaped members 3, and at opposite sides of the cutting and dislodging flange 5, and terminate in hooks 15 which extend through apertures 16 in the flange 5 and from opposite sides of the flange, therefore it will 50 be seen that the hooks 15 in connection with the handle as a whole will prevent threading of the flanges 4 which form the opposite sides of the cutting and dislodging flange 5.

From the above it will be seen that a plunger type of paint mixing device is provided which is positive in its operation, agitates on the upward and downward strokes and is provided with a cutting and dislodging flange extending below the agitator member, and which dislodging flange will cut into and break up paint pigments in the bottom of the can, or other solidified material. The device is particularly adapted 60 for use in mixing paints or for stirring 65

ready mixed paints which are sold in cans, however it will be seen the device may be used as a plunger agitator for other purposes. It will also be seen the agitating member is formed from a single sheet of 70 material, thereby allowing the device to be cheaply manufactured and sold. The device may be made any size desired, according to the size of the receptacle in which it is to be used. 75

The invention having been set forth what is claimed as new and useful is:—

1. The combination with an agitating device having a chamber in the underside thereof, of a cutting flange having notches 80 therein, said cutting flange extending below said agitating device and across said chamber and forming the same into independent chambers.

2. A plunger agitating device comprising 85 a body member having a chamber in the underside thereof, a downwardly extending flange extending across said chamber, upwardly extending flanges carried by opposite sides of the body member and terminating in spaced relation and an upwardly extending handle carried by said body member. 90

3. An agitating device comprising a body member having a chamber in the underside 95 thereof, said body member being rectangularly shaped, a diagonally disposed downwardly extending cutting and dislodging flange carried by the underside of the body member, oppositely disposed upwardly extending flanges carried by the body member and terminating in spaced relation to the other at the corners of the body member and an upwardly extending handle member carried by the body member. 100

4. The combination with a plunger agitator body having a chamber in the underside thereof, the upper side of said body member being formed from downwardly and outwardly inclined triangularly shaped 110 members, of upwardly extending flanges carried by the lower ends of the triangularly shaped members and terminating in spaced relation to each other.

5. An agitating member formed from a 115 single sheet of material bent to form a transversely disposed flange, triangularly shaped members formed integral with said flange, interengaging means between the adjacent portions of the triangularly shaped members 120 and means for preventing spreading of the flange.

6. An agitating device formed from a single sheet of material, said sheet of material being bent upon itself to form a downwardly extending flange, triangularly shaped interengaged members carried by the upper end of the portions forming the downwardly extending flange, interengaging means between the triangularly shaped portions, and 125 130

upwardly extending flanges carried by the outer ends of the triangularly shaped portions.

7. The combination with an agitating device having a transversely disposed downwardly extending rib formed from material bent upon itself thereby forming adjacent sections, a handle member, of arms carried

by the handle member and extending downwardly through apertures in the adjacent sections at opposite sides of the flange and through said flange. ¹⁰

In testimony whereof I hereunto affix my signature.

FREDERICK BECKORD.
